UNITED STATES PATENT OFFICE.

BÁRBARO JEREZ DIAZ, OF MADRID, SPAIN.

HAT PRESSING OR BLOCKING DEVICE.

1,106,635.

Specification of Letters Patent. Patented Aug. 11, 1914.

Application filed November 29, 1912. Serial No. 734,182.

To all whom it may concern:

Be it known that I, BÁRBARO JEREZ DIAZ, a subject of the King of Spain, and resident of Madrid, Spain, have invented certain new and useful Improvements in Hat Pressing or Blocking Devices, of which the following is a full, clear, and exact specification.

The present invention relates to improvements in hat shaping machines, particularly machines in which compressed air is used for molding the crowns of hats and the like. With this end in view an inflatable rubber bag is provided presenting a perfectly closed chamber provided with one single opening for the admission of the compressed air.

Heretofore bags have been used for the above mentioned purpose which were not perfectly closed and therefore presented the disadvantage that they permitted an easy escape of the compressed air and for this reason no lasting pressure could be obtained by using these bags. Therefore preferably hydraulic force was used for inflating these known bags and compressed air was simply used with special smaller air bags upon which the higher hydraulic force was acting. These hydraulically operated bags however had the disadvantage that they soon became untied by frequent use and thus became the cause for wetting the straw of the hats to be pressed. These disadvantages are all overcome by the use of a pressure bag according to the present invention which either consists of one part or is bi-partite and which presents one single perfectly closed chamber and which allows of an independent regulation of the pressure to suit the hat forms independent of their size.

In the accompanying drawings: Figure 1 is a perspective view of the pressure bag according to the present invention. Fig. 2 is a vertical section through the same. Fig. 3 shows a strengthening mantle for said bag. Fig. 4 is a section through the same. Fig. 5 shows a bi-partite pressure bag. Fig. 6 is a vertical section therethrough. Fig. 7 is a general view of the complete apparatus and Fig. 8 is a vertical section through the same.

The hat shaper comprises a closed rubber bag 1 of cylindrical or slightly conical shape provided upon its upper face with an opening 2 for the introduction of the means for supplying compressed air to said bag. This bag 1 is introduced in the well-known

manner into the interior of the crown of a hat to be pressed and is then inflated by compressed air.

In order to enlarge the diameter of the bag one or several caps can be drawn over the same as for instance shown in Figs. 3 and 4 in section, which cover the entire outer face of the bag with the exception of the central opening thereof. In this manner the body of the form is enlarged and greatly strengthened.

As shown in Figs. 5 and 6 the rubber bag can also be made in two parts instead of one single part and both parts are then telescopically engaging and this arrangement permits an adjustment of the height of the form.

A special device is provided for supplying the bag with compressed air and this device comprises an adjustable ball shaped head 7, Figs. 7 and 8, having a feeding tube 9 for the compressed air the lower, preferably conically shaped, end of which extends into the bag through the hole thereof. A ring 8 upon the face of the head part 7 allows an adjustment of the same with respect to the form.

The device operates as follows: After the hat to be pressed has been brought into the form the rubber bag is introduced into the crown of the hat with its supply opening for the compressed air on top. Hereafter the head 7 suitably arranged in the pressing machine is adjusted above the upper face of the rubber bag in such a manner that the point of the tube 9 extends into the opening of said rubber bag. If now compressed air is supplied to said bag the same is inflated and effects the pressing of the form.

I claim:

1. A device for pressing or blocking all kinds of hats, by means of the action of compressed air comprising in combination an india-rubber chamber, hollow and of continuous surface and of a slightly conical form, having an orifice in one of its bases for the admission of compressed air and an apparatus for the injection of said compressed air, comprising a semi-spherical metal piece traversed through its pole or center by a compressed air tube.

2. In a hat shaping and pressing machine the combination with a hat die of a closed rubber bag provided with an opening in its upper face, and of a ball shaped head provided with a ring for adjustment of said

head with respect to said die, and of a tube extending with its lower conically shaped end through said opening into said rubber bag for supplying compressed air to the same.

3. In a hat shaping and pressing machine in combination with a hat die, a rubber bag comprising two telescopically engaging parts, the upper provided with an opening and adjustable means extending into said opening for supplying compressed air to said bag through said opening.
- 10 4. In a hat shaping and pressing machine

the combination with a hat die of a closed rubber bag provided with an opening in its upper face, of means for strengthening and enlarging the outer diameter of said bag and of means for supplying compressed air to said bag through said opening.

In testimony that I claim the foregoing as my invention, I have signed my name in presence of two subscribing witnesses.

B. JEREZ DIAZ.
